UNITED STATES PATENT OFFICE.

CHARLES A. TRUAN, OF KNOXVILLE, TENNESSEE.

SAFE AND VAULT DOOR.

Application filed March 23, 1922. Serial No. 546,048.

To all whom it may concern:

Be it known that I, CHARLES A. TRUAN, a citizen of the United States, residing at Knoxville, in the county of Knox and State 5 of Tennessee, have invented a new and useful Improvement in Safe and Vault Doors, of which the following is a specification, reference being had to the accompanying drawing.

10 My invention relates particularly to locks for safes and vaults and similar doors which are intended to be secured against the efforts of burglars to open the doors.

15 The object of my improvement is to provide a secondary locking mechanism which will automatically make engagement to resist movement of the bolt-carrying bar when it is undertaken to disable the main locking mechanism to such extent as to allow the 20 shifting of the bolt-carrying bar to release the door.

The secondary mechanism includes means whereby an authorized person may release 25 said mechanism after it has been automatically put into engagement.

In the accompanying drawings,

Fig. 1 is a view of the inner face of a safe door to which my improvement has been applied;

30 Fig. 2 is an upright section on the line, 2—2, of Fig. 1, looking toward the left;

Fig. 3 is a section on the line, 3—3, of Fig. 2, looking toward the left;

35 Fig. 4 is another view of a part of the mechanism shown by Fig. 3, the rotary member being in the locking position;

Fig. 5 is a horizontal section on the line, 5—5, of Fig. 3;

40 Fig. 6 is a perspective of the hook bolt which forms a part of the secondary locking mechanism;

Fig. 7 is a perspective of the rotary member with which said bolt is associated;

Fig. 8 is a horizontal section on the line, 45 8—8, of Figs. 1 and 10, looking upward;

Fig. 9 is an upright section on the line, 9—9, of Fig. 1, looking toward the right;

Fig. 10 is an elevation of a box wherein the solenoids are located;

50 Fig. 11 is a perspective of the base or support for the solenoids;

Fig. 12 is a diagrammatic view showing signal devices associated with the main lock and the auxiliary lock.

Referring to said drawings, A is the stationary frame around the door opening. A¹ are hinges supporting said door on said frame. A² are sockets in the frame, A, which receive the ends of the main locking bolts. B is the body of the door. B¹, B² are the usual edge bars extending along the inner face of the door near its four edges. In the edge bars are bearings, B², in which rest the main bolts, B³. The horizontal bolts, B³, are long and have both ends resting in bearings, 55 B². The short main bolts, B³, have the outer end resting in said bearings, and the inner end in a bearing, B⁴, and said bolts are supported by one arm of a bell crank, B⁵; the other arm of the bell-crank being coupled to the adjacent long bolt, B³, in such manner as to cause the short bolt to retract or move forward when the adjacent long bolt is retracted or moved forward. B⁶ is the usual bolt-carrying bar. This is upright and extends across the long main bolts near the outer upright edge bar. The bar, B⁶, is immovably secured to the long bolts, B³, by means of bolts, B⁷, whereby said bar and said main bolts are made a unitary bolt 75 frame to slide horizontally in the bearings, B², in the upright edge bars, B¹, in the usual manner. When said frame is moved toward the outer edge bar, the outer ends of the long main bolts, B³, enter the sockets, A², and the 80 short bolts, B³, enter the lower sockets, A², of the door frame, in the usual manner. For unlocking the door, this movement is reversed. The bolt frame is to be shifted by means of a shaft (not shown) extending outward through the door and having a handle at its outer end, in the usual manner. The reverse or unlocking movement of said frame is prevented in the usual manner by connection between the main lock, C, and said 85 frame, said lock being usually of the combination type. One of the methods used by burglars for opening a safe or vault door involves the disabling or destroying of the main lock, C, to such extent as to render that 90 lock incapable of holding the bolt frame against reverse movement, the bolt frame being then reversed by means of the handle above-mentioned or by reaching with a tool through the opening made at the lock. Said 95 lock may be disabled by driving the combination stem inward with a hammer, or by drilling holes around the stem, C¹, of the

lock until said bolt and associated members may be displaced, or by fusing the metal around the bolt until said bolt and associated parts can be displaced, or by explosion.

- 5 My improvement comprises a secondary locking mechanism which is set into the locking position to hold the bolt frame when the main lock has been disabled or destroyed by any such means as are mentioned 10 above. In the secondary mechanism, D is an anchor bolt. Said bolt extends horizontally through the edge bar, B¹, the body of said bolt being screw-threaded into said bar and the cross head, D¹, of said bolt extending 15 toward the bolt-carrying bar, B⁶, and being in an upright plane which passes between said bar and the body of the door, B. The opposite end of said bolt projects through said bar and the threading on said 20 bolt extends to said end. A nut, D², is threaded on said end and is turned to jam against the outer face of the edge bar when said bolt has been turned to bring it into the desired position. Said jam nut then 25 serves to secure said bolt immovably. D³ is a rotary member by means of which the anchor bolt is engaged when the secondary locking mechanism is put into action. The body of the rotary member is disc-form and 30 has at its center a forward-directed hub, D⁴, through which and the bar, B⁶, extends a bolt, D⁵. The head of said bolt is countersunk into said hub, and the bolt has a shoulder, D⁶, which bears against the forward face of the bar, B⁶. Thus the rotary member is held for free rotation on said bolt, the bolt serving as a journal. Along the periphery of said rotary member is a 35 flange, D⁷, which extends nearly around said member, there being a gap large enough to allow the cross-head, D¹, to pass. At one end, said flange has a slot, D⁸, which is parallel to the bar, B⁶, and in the plane of the anchor bolt, D. 40 Said rotary member is so placed on the bolt-carrying bar, B⁶, as to cause the cross head D¹, of the anchor bolt, D, to pass through the gap in the flange, D⁷, and stand in the annular space between said flange 45 and the hub, D⁴, when the bolt frame is moved into the locking position. As long as the rotary member is in this position, the bolt frame may be shifted into and out of the locking position without engagement 50 between the rotary member and the anchor bolt. But when the bolt frame is in the locking position and the cross head of the anchor bolt is in position in said annular channel in the rotary member, the rotation of said member in the proper direction 55 to move the channel, D⁸, toward the anchor bolt, the parts of the flange, D⁷, at each side of said channel will move astride the bolt, the cross head still remaining in said channel. Then, when effort is made to reverse 60
- the bolt frame out of the locking position, the flange, D⁷, will make engagement with the cross head and movement of the bolt frame will be prevented, although the main lock may have been deranged or removed 70 so that it no longer serves to prevent the moving of the bolt frame out of the locking position. The rotary member, D³, is turned automatically into its locking position by means which will next be described. 75
- On the bar, B⁶, above the rotary member is a horizontal post, D⁹, into the free end of which post is driven a screw, D¹⁰, (Figs. 2 and 3) extending through a slot, D¹², in an oscillating bar, D¹¹, extending across the 80 rotary member in a plane which is parallel to the plane of the bolt-carrying bar. In the oscillating bar opposite the lower part of the flange, D⁷, is a slot, D¹³. A screw, D¹⁴, extends through said slot and into said 85 flange and is held immovably. Both of said slots are large enough, and the heads of said screws are sufficiently free from said bar to permit the bar to slide endwise on said screws. The screw, D¹⁴, serves as a 90 wrist on the rotary member, and the rotary member serves as a crank wheel which is to be given only partial rotation. The oscillating bar, D¹¹, oscillates with the screw, D¹⁰, as a fulcrum. When said bar is oscillated, the rotary member is partially turned far enough to cause the flange of the rotary member to engage the cross head, D¹, of the anchor bolt, D. The endwise movement of the oscillating bar, D¹¹, is provided in order 95 that its lower or free end may move in a right line to adapt it for connection with the below-described solenoid core, which is confined to right line movement.
- A rectangular box, E, is secured to the inner face of the door opposite the rotary member, D³, and is open toward the interior 100 of the safe and has over the opening a lid, E¹, comprising a frame, E², and a body of glass, E³, and hinged to the lower edge of the 105 box. In the lower part of the box is placed a solenoid base, E⁴, comprising two rectangular compartments, E⁵, connected by a web, E⁶. The upright walls of the compartments, E⁵, have horizontal apertures, E⁷, which are in the 110 same horizontal line, and in said line is also the lower or free end of the oscillating bar, D¹¹. On the same line each upright wall of the box, E, has an aperture, E⁸. A brass tube or bushing, E⁹, extends through the apertures, E⁷ and E⁸, and at the outer face of each of said upright box walls said bushing is surrounded by a retaining ring, E¹⁰, whereby said bushing is held against endwise 115 movement. In said bushing is a solenoid core, E¹¹, which is slidable endwise and projects from said tube at one end far enough to meet and be coupled at, E¹², to the lower or free end of the oscillating bar, D¹¹. Adjacent the box, E, the projecting part of the 120
- 125
- 130

core is screw-threaded and receives a ring-form nut, E¹³, which may be moved on the core into the desired position to constitute a stop for limiting the movement of the core 5 into the brass bushing, E⁹.

When the solenoid core is reciprocated, the oscillating bar is oscillated, whereby the rotary member is partially turned. The main part of the core is steel; but in each 10 compartment, E⁵, the solenoid has a short section, E¹⁴, of brass. In each compartment, E⁵, the brass bushing, E⁹, is surrounded by a wire coil, E¹⁵. One of said coils is wound for moving the core in one direction and the other coil is wound for moving the core in the opposite direction. The coil which controls the movement of the core, E¹¹, in the direction for turning the rotary member out of its normal position and 15 into the position for engaging the cross head of the anchor bolt is on an electric circuit which includes a battery and the main lock mechanism, the circuit being open at the main lock. Between the box, E, and the 20 body, B, of the safe door is a plate of zinc or other conducting metal, E¹⁶, and at each side of said plate is a layer of insulation, E¹⁷. A screw, E¹⁸, extends through the back wall of the box, E, into the door, B. A 25 bushing, E¹⁹, of insulation material surrounds said screw in the plate, E¹⁶, whereby the screw is insulated from said plate. The function of said screw is to make electrical connection between the box, E, and the door, 30 B. Between the body, C, of the main lock and the door is a plate of zinc or similar conducting metal, C², and C³ are layers of insulation material at each side of the metal plate, C². An insulation bushing, C⁴, surrounds the 35 stem, C¹, of the lock, whereby the plate, C², is insulated from said stem. Above the lock, a binding screw, C⁵, extends through the outer layer of insulation and into the metal plate, C². Below the box, E, a binding screw, E²⁰, 40 extends through the outer insulation layer, E¹⁷, and into the metal plate, E¹⁶. A wire, W, extends from the binding screw, C⁵, to the binding screw, E²⁰, and thence to said coil, E¹⁵, and thence to the battery, F, and 45 from the battery to the screw, E¹⁸.

A metal bracket, C⁶, is secured by a screw, C⁷, to the metal plate, C², said screw extending through the base of the bracket and the adjacent layer of insulation into the plate, 55 C². Said bracket extends away from the door, parallel to the lower face of the lock, beyond said face and then upward parallel to the rear face of the lock and spaced from said face far enough to admit a metal plate, 60 C⁸, to be supported by the bracket between the latter and the lock without touching the lock.

At the lock the circuit has now a gap or 65 break between the said door, B, and the metal plate, C², and also between the lock

and the plate, C⁸, of the bracket, or between any part of the bracket and the lock. From the plate, C², the circuit extends through the wire, W, and the right hand coil, E¹⁵, and from the coil to the wire, W, to the main 70 battery, F, and from the battery through the wire, W, to the screw, E¹⁸, and through the latter to the door, and through the door to lock stem, C¹, and through said stem to the lock. Drilling through the door around the 75 stem, C¹, will cause the drill tool, G, (Fig. 9) to touch the door and the metal plate, C². In that position, the tool closes the gap or break in the circuit, and the coil, E¹⁵, is then energized for shifting the solenoid core, 80 E¹¹, toward the right. Burning through the door instead of drilling will destroy the insulation material between the door and the metal plate, C², whereby said plate and the door will make contact and close the circuit. 85 If the stem, C¹, of the lock is driven inward by hammer blows so as to drive the lock inward, the lock will touch the bracket, C⁶, or the plate, C⁸, whereby the circuit will be closed. (See Fig. 9.)

When the rotary member has been put into engagement with the anchor bolt through effort by an unauthorized person to derange or destroy the main lock, the other solenoid core is to be energized for retracting the core, E¹¹, for reversing the rotary member into its rest position, the gap in the flange of the rotary member being brought around the anchor bolt, so that the rotary member may be carried away by the bolt 95 frame without hindrance by the anchor bolt. For the purpose of energizing the second coil, a circuit is provided which is independent of the main lock. At any desired point on the inner face of the body, B, of the door 100 is placed a metal plate, H, between which and the door is a layer of insulation, H¹. A wire, W, leads from the plate, H, to the second coil and from said coil to the battery and from the battery to the screw, E¹⁸. Thus 105 a circuit is formed with only a gap between the plate, H, and the door, said gap being occupied by the layer of insulation, H¹. By now drilling through the door from the outside with a small drill until the plate, H, is 110 touched, said gap is closed by the drill tool. Then the energized second coil draws the core, E¹¹, away from the free edge of the door, whereby the rotary member is turned to release itself from the anchor bolt.

While applying the apparatus, the plate, H, and its layer of insulation, H¹, are put arbitrarily any where on the inner face of the door at a place which can be reached with a drill. The chosen location is noted 125 on a chart or diagram which is kept in a secret place for reference when it becomes necessary to close the electric circuit between the door and the plate, H, for the retracting of the solenoid core. The plate, H, may be so 130

small that a burglar might drill the door in many places without touching said plate.

On the electric circuit between the main locking mechanism and the right hand solenoid coil which serves to put the auxiliary locking mechanism into engagement is a fuse plug, I , which is adapted to "blow" under development of heat when that circuit has been closed a chosen length of time. When 10 that has occurred, the auxiliary locking mechanism will remain in engagement until the circuit through the other solenoid coil has been closed in the manner already described or in any other manner. If it is 15 found that said fuse has not "blown", it may be blown by placing increased current on that circuit. If the main locking mechanism has been sufficiently deranged to afford access to the interior parts for breaking that 20 circuit, no heat need be given to the fuse plug. And the insertion of the fuse plug in this circuit may be altogether omitted and reliance placed on breaking the circuit at the main locking mechanism when the auxiliary 25 locking mechanism has been put into engagement by attempt to open the door by deranging the main locking mechanism.

The signal devices illustrated by Fig. 12 are associated with the main lock and with 30 the auxiliary locking mechanism and with a hand switch and a foot switch. The signal means may be any devices suitably located to actuate when the main lock is deranged by an intruder or the auxiliary locking mechanism moves into operating position or when 35 an attendant, on seeing intruders, actuates either the hand switch or the foot switch.

In Fig. 12, the wires, J^3 and J^4 , are circuit wires on which are the auxiliary battery, M , and an electric horn or similar sounding device, K . A wire, C^9 , connects the wire, J^3 , with the main lock, C . Another wire, C^9 , connects the wire, J^4 , with the door, b . When the circuit is closed between the door and the main lock in the manner above described or suggested, current passes through the wires to the horn, K , and said horn then sounds as long as the circuit remains closed. The drawing also 50 shows two incandescent lamps, L , connected to the wires, J^3 and J^4 , by branch wires, L^1 and L^2 . When the circuit becomes closed, as above mentioned, for sounding the horn, current also passes through the lamps, L , and the light thus produced indicates abnormal condition at the safe or vault door or in the vicinity of the safe or vault.

Adjacent the right hand end of the solenoid core are two blade-form electrodes or 60 brushes, J , secured to supports, J^1 , by screws, J^2 . One of said screws binds the wire, J^3 , to the adjacent electrode, while the other screw, J^2 , binds the wire, J^4 , to the adjacent electrode. The distance between the electrodes, 65 J , is a little less than the diameter of the

nut, E^3 , carried by the solenoid core, E^1 . When the said core is driven forward for actuating the auxiliary locking mechanism, the nut, E^3 , is moved forward and touches said electrodes, whereby the circuit of which 70 the wires, J^3 and J^4 , form parts is closed. This condition remains until the solenoid core has been retracted. The provision for automatically closing the signal circuit is made double for the sake of attaining certainty of action and of making certain that 75 said circuit will remain closed until such time as it is desired to restore normal conditions.

The floor switch N , may be of any desired form suitable to be actuated by pressure with the foot. Such a foot switch may be placed at any point near to a person who is on duty and can see a person who is or is thought to be a criminal intruder. When 80 said switch is pressed, the circuit through the horn, K , and the lamps, L , L , is completed.

Wires, O^1 , O^1 , lead from the hand switch, O , to the wires, N^1 , N^1 . When that switch is closed, the circuit is completed through 90 the horn, K , and the lamps, L , L . This hand switch may be placed at any point which may be conveniently reached by a person on duty when seeing a person who is or is thought to be a criminal intruder. The 95 signal horn and the signal lamps—any number of these—are preferably placed outside of the building in which the safe or vault is located.

It will now be observed that there is inter-relation and co-operation between the main lock and the auxiliary locking mechanism and the signal devices, the auxiliary locking mechanism and the signal devices being at all times ready to go into action when the 105 main lock is disturbed or deranged.

I claim as my invention,

1. In an apparatus of the kind described, the combination with a door, of a main locking mechanism, and an auxiliary locking 110 mechanism including a member stationary on the door and electro-magnetic means and movable engaging means supported on the bolt frame and in operative relation with the main locking mechanism for automatically putting said auxiliary locking mechanism into engagement for holding the bolt frame when derangement of the main locking mechanism is attempted, substantially 115 as described.

2. In an apparatus of the kind described, the combination with a door, of a main locking mechanism, and an auxiliary locking mechanism including a member stationary 120 on the door and solenoid means and movable engaging means supported on the bolt frame and in operative relation with the main locking mechanism for automatically putting said auxiliary locking mechanism into engagement for holding the bolt frame 125 130

when derangement of the main locking mechanism is attempted, substantially as described.

3. In an apparatus of the kind described, 5 the combination with a door, of a main locking mechanism, and an auxiliary locking mechanism including a member stationary 10 on the door and solenoid means and movable door-engaging means supported on the bolt frame 15 and in operative relation with the main locking mechanism for automatically putting said auxiliary locking mechanism into engagement for holding the bolt frame when derangement of the main locking mechanism is attempted and under the control of 20 an authorized person putting the auxiliary locking mechanism out of engagement, substantially as described.

4. In an apparatus of the kind described, 25 the combination with a door, of a main locking mechanism, and an auxiliary locking mechanism including a stationary member and a movable member adapted for inter- 30 engagement, the stationary member being on the door and the movable member being on 35 the bolt frame, and electro-magnetic means in operative relation with the main locking mechanism for automatically shifting said movable member into engagement with the stationary member when derangement of the 40 main locking mechanism is attempted, substantially as described.

5. In an apparatus of the kind described, 45 the combination with a door, of a main locking mechanism, an auxiliary locking mechanism including a stationary member and a movable member adapted for inter-engagement, one of said members being stationary 50 on the door and the other being movable on the bolt frame, and electro-magnetic means in operative relation with the main locking mechanism for automatically shifting said movable member into engagement with the stationary member when derangement of the 55 main locking mechanism is attempted and under the control of an authorized person shifting the said members out of inter-engagement, substantially as described.

6. In an apparatus of the kind described, 60 the combination with a door, of a main locking mechanism, an auxiliary locking mechanism including a stationary member and a movable member adapted for inter-engagement, one of said members being stationary 65 on the door and the other being movable on the bolt frame, and solenoid means in operative relation with the main locking mechanism for automatically shifting said movable member into engagement with the stationary member when derangement of the main locking mechanism is attempted and under the control of an authorized person shifting the said members out of inter-engagement, substantially as described.

65 7. In an apparatus of the kind described,

the combination with a door, of a main locking mechanism, and an auxiliary locking mechanism, and electro-magnetic means and movable door-engaging means supported on the bolt frame and in operative relation with the main locking mechanism for automatically shifting said auxiliary locking mechanism into engagement for holding the bolt frame when derangement of the main locking mechanism is attempted, and electro- 70 magnetic means for releasing the auxiliary locking mechanism, said electro-magnetic means comprising means for forming an electric circuit which is open at a place to be reached by a drill tool inserted through 75 the door from the front, substantially as described.

8. In an apparatus of the kind described, the combination with a door, of a main locking mechanism, and an auxiliary locking mechanism, and electro-magnetic means in operative relation with the main locking mechanism for automatically putting said auxiliary locking mechanism into engagement when opening the door by derangement 80 of the main locking mechanism is attempted and under the control of an authorized person shifting the auxiliary locking mechanism out of engagement, and means including wiring and an insulated plate on the inner 85 face of the door forming a partial circuit including the electro-magnetic means, said circuit being open between said plate and the door, whereby said circuit may be closed by inserting a drill tool through the door 90 opposite said plate, substantially as described.

9. In an apparatus of the kind described, the combination with a door, of a main locking mechanism, an anchor member and a rotary member adapted for inter-engagement, one of said members being supported on the door and the other being supported on the bolt frame, and electro-magnetic means in operative relation with the main locking 100 mechanism for shifting said rotary member into engagement with said anchor member, substantially as described.

10. In an apparatus of the kind described, the combination with a door, of a main 115 locking mechanism, an anchor member and a rotary member adapted for inter-engagement, one of said members being supported on the door and the other being supported on the bolt frame, and electro-magnetic 120 means in operative relation with the main locking mechanism for shifting said rotary member into engagement with said anchor member and under the control of an authorized person shifting said rotary member out 125 of engagement with said anchor member, substantially as described.

11. In an apparatus of the kind described, the combination with a door, of a main locking mechanism, an anchor member stationary 130

on the door, a rotary member seated on the bolt frame and adapted to make inter-engagement with the anchor member, and electro-magnetic means for actuating said 5 rotary member, substantially as described.

12. In an apparatus of the kind described, the combination with a door, of a main locking mechanism, an anchor member stationary on the door, a rotary member seated on 10 the bolt frame, and adapted to make inter-engagement with the anchor member and solenoid means for actuating said rotary member, substantially as described.

13. In an apparatus of the kind described, 15 the combination with a door, of a main locking mechanism, and an auxiliary locking mechanism including electro-magnetic means a movable door engaging means supported on the bolt frame and in operative relation 20 with the main locking mechanism for automatically putting said auxiliary locking

mechanism into engagement for holding the bolt frame when derangement of the main locking mechanism is attempted, and fusible means associated with said electro-magnetic 25 means, substantially as described.

14. In an apparatus of the kind described, the combination with a door, of a main locking mechanism and an auxiliary locking mechanism including duplex solenoid means 30 in operative relation with the main locking mechanism for automatically putting said auxiliary locking mechanism into engagement and under the control of an authorized person putting the auxiliary locking 35 mechanism out of engagement, substantially as described.

In testimony whereof I have signed my name, this 1st day of March, in the year one thousand nine hundred and twenty-two. 40

CHARLES A. TRUAN.
